Primary Examiner — Karen E Kearney*Assistant Examiner* — Megan M Majcher Hartnett(74) *Attorney, Agent, or Firm* — Yee & Associates, P.C.(57) **CLAIM**

The ornamental design for a display screen with graphical user interface, as shown and described.

DESCRIPTION

FIG. 1 is a view of an embodiment of a display screen with graphical user interface; and,

FIG. 2 is a view of another embodiment thereof.

The broken line showing of the display screen is for the purpose of illustrating environment and forms no part of the claimed design. The broken line showing of elements on the display screen illustrate portions of the graphical user interface that form no part of the claimed design.
